Primary Examiner — Melody N Brown*(74) Attorney, Agent, or Firm* — Westman, Champlin & Koehler, P.A.; Z. Peter Sawicki; Amanda M. Prose(57) **CLAIM**

The ornamental design for a vehicle fan housing, as shown and described.

DESCRIPTION

FIG. 1 is a front and right side perspective view of a vehicle fan housing showing my new design;

FIG. 2 is a front elevation view thereof;

FIG. 3 is a top and front perspective view thereof; and,

FIG. 4 is a front and left side perspective view thereof.

The bottom and rear of the vehicle fan housing are not visible during normal use.

The portions of the vehicle shown in a de-emphasized halftone and faded out form is for illustrative and environmental purposes that form no part of the claimed design.
